UNITED STATES PATENT OFFICE.

CHARLES E. OSMER AND JOSEPH BARR ROACH, OF BEARDSTOWN, ILLINOIS.

ELECTRODE.

1,127,499.

Specification of Letters Patent.

Patented Feb. 9, 1915.

Application filed March 9, 1914. Serial No. 823,521.

To all whom it may concern:

Be it known that we, CHARLES E. OSMER and JOSEPH BARR ROACH, citizens of the United States, residing at Beardstown, in the county of Cass and State of Illinois, have invented certain new and useful Improvements in Electrodes, of which the following is a specification, reference being had to the accompanying drawings.

10 This invention relates to certain improvements in electrodes and has relation more particularly to a device of this general character especially designed and adapted for use in connection with locomotive headlights; and the object of the invention is to provide a novel and improved device of this general character which may be maintained in operative position within the lamp without the necessity of the auxiliary holder generally employed in devices of this character and whereby the electrode is rendered a better conductor of heat and thus reduce to a minimum the possibility of the copper fusing or burning.

25 The invention consists in the details of construction and in the combination and arrangement of the several parts of our improved electrode whereby certain important advantages are attained and the device is rendered simpler, less expensive and otherwise more convenient and advantageous for use, all as will be hereinafter more fully set forth.

The novel features of the invention will be 35 carefully defined in the appended claims.

In order that our invention may be the better understood, we will now proceed to describe the same with reference to the accompanying drawings, wherein—

40 Figure 1 is a view in side elevation of an electrode constructed in accordance with an embodiment of our invention, the same being shown in applied position, the coacting clamping holder being indicated by dotted lines; Fig. 2 is an enlarged view in front elevation of the electrode as disclosed in Fig. 1; Fig. 3 is a sectional view taken substantially on the line 3—3 of Fig. 2; and Fig. 4 is a sectional view taken substantially 50 on the line 4—4 of Fig. 2.

As disclosed in the accompanying drawings, 1 denotes a clamp holder of conventional form having suitably engaged therewith, the carbon 2 and positioned therebelow is the electrode 3 constructed in accordance with an embodiment of our present

invention. As herein disclosed, our electrode 3 comprises an elongated member substantially circular in cross section and having its upper extremity pointed, as at 4, 60 while its lower extremity is rounded or offset, as indicated at 5, and terminates in the flattened extension 6, such extension being disposed in substantial parallelism with the body portion proper of the electrode 3 and 65 is adapted to be inserted within the holder 1 whereby it will be readily perceived that the electrode 3 is maintained in proper position without the necessity of an auxiliary or independent holder. This arrangement 70 of the electrode permits the use of one of greater dimensions than is commonly employed whereby such electrode is a better heat conductor and consequently preventing the same from fusing or burning. 75

From the foregoing description, it is thought to be obvious that an electrode constructed in accordance with our invention is of an extremely simple and comparatively inexpensive nature and is particularly well 80 adapted for use by reason of the convenience and facility with which the same may be employed and by reason of the lengthened period of time the same may be used in comparison with devices of a similar character 85 now generally used, and it will also be obvious that our invention is susceptible of some change and modification without material departure from the principles and spirit thereof and for this reason we do not 90 wish to be understood as limiting ourselves to the precise arrangement and formation of the several parts herein shown in carrying out our invention in practice. 95

We claim:

1. As a new article of manufacture, an electrode comprising an elongated member having one extremity tapered and its opposite extremity offset, such offset extremity being provided with a flattened extension 100 disposed in substantial parallelism with the body portion of the elongated member.

2. As a new article of manufacture, an electrode comprising an elongated member having one extremity tapered and its opposite extremity offset, such offset extremity being provided with a flattened extension 105 disposed in substantial parallelism with the body portion of the elongated member, such elongated member being substantially circular in cross section.

3. As a new article of manufacture, an

electrode having one extremity offset relative to the major portion thereof, said offset portion serving as a securing means.

4. As a new article of manufacture, an electrode having one extremity offset relative to the major portion thereof, said offset portion serving as a securing means, said offset portion being flattened.

In testimony whereof we hereunto affix our signatures in the presence of two witnesses.

CHARLES E. OSMER.
JOSEPH BARR ROACH.
